UNITED STATES PATENT OFFICE.

HANS RUKOP, OF BERLIN, GERMANY, ASSIGNOR TO GESELLSCHAFT FÜR DRAHTLOSE TELEGRAPHIE M. B. H. HALLESCHIES, OF BERLIN, GERMANY, A CORPORATION OF GERMANY.

CIRCUIT ARRANGEMENT FOR GENERATING OSCILLATIONS.

Application filed December 27, 1922, Serial No. 609,185, and in Germany February 11, 1922.

The German Patent, No. 304,283, describes special circuit arrangements for generating continuous electrical oscillations for the purpose of keeping sending waves as constant as possible notwithstanding variations in the circuits, for example, variations due to poor antennae. It is known that the natural wave length of an antenna circuit may vary over a wide range due to change in the position of the antenna relative to the ground and other objects, due to winds, etc. The arrangement is so constituted that the energy which is used up is derived mainly from one circuit, whereas the wave length is determined by a second additional system which is maintained as constant as possible.

The present application pertains to a special circuit arrangement operating according to like principles.

In the drawings Fig. 1 shows the circuit arrangement as a whole and Fig. 2 shows the relation between the wave lengths of the two coupling waves produced in two coupled tuned circuit and the factors varying the wave length of one of those circuits.

In accordance with the present invention, an oscillating circuit is provided for supplying the energy, e. g. an antenna circuit I, and a second oscillating circuit II is provided which is free of losses and is constant. The circuit arrangement as a whole may be as shown in Fig. 1, i. e. like that shown in Fig. 1 of said patent. The circuit consists of a three element thermionic tube T having the circuit II connected across its grid and cathode. The circuit II consists of an inductance 1 and capacitance 2 connected in parallel which are kept constant under operating conditions. Connected across anode and cathode is inductance 3 which is coupled to inductance 1 for producing sustained oscillations in the well-known way, and anode supply direct current generator 4.

Connected also across the anode and cathode is the primary of transformer 5 in series with condenser 6. The secondary of transformer 5 is connected in the antenna circuit.

It will be seen that the two circuits I

and II may be loosely or closely coupled with each other depending on the values of the circuit arrangement. 55

In accordance with the present invention, first, the two circuits are noticeably detuned with respect to each other, second, the coupling of the two circuits is somewhat close, that is to say, not very loose, and, third, 60 the back-coupling between the circuits, or any auxiliary means in its stead, is provided in such a manner that of the wave lengths that may come out of the coupling circuit only that one will energize itself which is 65 near the individual natural wave of the constant circuit II and not that one which is near the natural wave of the variable circuit I.

The last-mentioned condition is based up- 70 on the well known fact, that if two circuits of different natural wave-lengths be coupled together, the resonance points are not at the natural wavelengths of the single circuits, but the resonance curve of the resultant circuit arrangement will be found to have two peaks. For convenience I have designated the wavelengths of these two peaks as "coupling waves" or "coupling wavelengths". One coupling wave is longer 75 80 than the longest of the two individual natural waves but is quite near to it. On the other hand, the other coupling wave is shorter than the shortest of the two individual natural waves and is equally near 85 to it. The substantially constant character of the sending wave length enables the coupling wave which, as explained above and in accordance with the above stated conditions, is very near the individual natural 90 wave of the constant circuit II, to be made independent of the individual natural wave of the circuit I, so as not to be appreciably affected by variations in the circuit I. This 95 relation is illustrated in Fig. 2, in which it is assumed that the natural wave length of the circuit II is constant and that the natural wave length of the circuit I is variable within wide limits. The conditions which cause variations in the natural wave length of the circuit I, including variable capacity or self induction, serve as the abscissa. The ordinate represents wave length.

The line A—A denotes the individual nat-

ural wave length of the circuit I, which varies in proportion with the changes in the conditions represented by the abscissa. The line B-B denotes the natural wave length of the circuit II which is constant. The wave lengths which may be actually generated in the system are shown by C and D. The system is operated at one of the points in the diagram which show a considerable constancy of the energized wave lengths notwithstanding variations in the natural wave length of the circuit I, e. g. around P or Q. The longer wave C appears as constant in the neighborhood of P and the shorter wave D in the neighborhood of Q notwithstanding the variations in circuit I.

It will be seen, therefore, that in accordance with the above principle the constant circuit may either have a natural wave length greater than that of the variable circuit as at P or smaller as at Q. It is advisable to use a back-coupling arrangement which prevents the cutting over of the sender into the other coupling wave.

The manner in which these circuits are coupled, that is to say, whether they are electrically or mechanically coupled or whether special intermediate elements such as coils or inductances are used, is without any importance from the standpoint of the present invention.

Having described my invention what I claim is:

1. In a vacuum tube oscillation generator having an input and output circuit regeneratively coupled, the combination of a first circuit having a first natural wavelength, a second circuit having a second natural wavelength which is substantially different from said first wavelength, coupling means such that when said first and second circuits are taken together they have coupling wavelengths, and means for impressing one of said coupling wavelengths upon the input circuit of the generator.

2. In a vacuum tube oscillation generator having an input and output circuit regeneratively coupled the combination of a first circuit having a first natural wavelength, a second circuit having a second natural wavelength which is substantially different from said first wavelength, coupling means such that when said first and second circuits are taken together they have coupling wavelengths, and means whereby one of said coupling wavelengths is accentuated.

3. In a vacuum tube oscillation generator having an input and output circuit regeneratively coupled the combination of a first circuit having a first natural wavelength, a second circuit having a second natural wavelength which is substantially different

from said first wavelength, coupling means such that when said first and second circuits are taken together they have coupling wavelengths, and means for amplifying one of said coupling wavelengths.

4. In a vacuum tube oscillation generator having an input and output circuit regeneratively coupled the combination of a first circuit having a first natural wavelength, a second circuit having a second natural wavelength which is substantially different from said first wavelength, coupling means such that when said first and second circuits are taken together they have coupling wavelengths, and amplifying means associated with said first circuit whereby only the coupling wavelength which is nearest said first wavelength is amplified.

5. In combination, an oscillator having its input and output circuits regeneratively coupled to produce sustained oscillations, one of said circuits having a first natural wave length, a third circuit coupled to the other of said two first mentioned circuits, and having a second natural wave length which is substantially different from said first wave length, means for coupling said circuits having natural wave lengths to produce coupled wave lengths, and means for radiating the coupled wave length which is nearest to said first mentioned wave length.

6. In combination, an oscillator having its input and output circuits regeneratively coupled to produce sustained oscillations, said input circuit having a first natural wavelength, a work circuit coupled to said output circuit and having a second natural wavelength which is substantially different from said first wavelength, said coupled circuits taken together having coupling wavelengths, and means whereby only the one of the resulting coupling wavelengths which is nearest the first natural wavelength is generated.

7. In combination, a thermionic tube having an anode, grid and cathode, a first circuit comprising an inductance and a source of direct current in series with said anode and cathode, a grid circuit comprising an inductance and capacitance in parallel connected between said grid and cathode, said inductances being coupled to each other, said grid circuit having a first natural wavelength, a second circuit connected in series with said anode and cathode, an antenna circuit coupled to said second circuit and having a natural wave length substantially different from said first wavelength, whereby only the one of the coupling wavelengths resulting from the interaction of the circuits on each other which is nearest the first natural wavelength is generated.

HANS RUKOP.
